ELECTRICAL COMMUNICATION SYSTEM

Paul O. Farnham, Boonton, N. J., assignor, by
mesne assignments, to Radio Corporation of
America, New York, N. Y., a corporation of
Delaware

Application June 8, 1929, Serial No. 369,287

4 Claims. (Cl. 250—20)

This invention relates to an electrical communication system and particularly to an input system for use with a radio frequency amplifier.

In designing a radio receiver for operation over a band of frequencies, the engineer is confronted with the fact that the stage gain-wave length curve falls off rapidly with increasing wave length. In addition to this varying amplification which characterizes the usual stage or stages employing 10 tuned transformer or impedance coupling, a further variation, and in the same sense, arises within the input system which precedes the first amplifier. While it is possible to construct amplifier stages having a flattened gain-wave length 15 characteristic, it will be apparent that the design of an amplifier may be materially simplified if the input system is given such properties that, for a given signal strength in the antenna, the voltage impressed upon the first amplifier increases with increasing wave length.

In considering the operation of an input system, reference is usually made to the step-up of the system, which step-up is given by the ratio of the first stage input voltage E to the voltage 25 E_0 induced in the antenna.

An object of the present invention is to provide an input system which operates to flatten, or if desired to reverse the slope of, the curve which represents the variation of step-up with 30 wave length.

An object is to provide an input system which will equalize the gain over the operating range of a receiver by reducing the step-up at the higher frequencies.

35 A further object is to provide an input system which operates, throughout the frequency range to which an amplifier may be tuned, to give the effective impedance from which the receiver operates an inductive character.

40 More specifically, an object is to provide an input system including, between the receiver and an antenna, a reactive impedance resonant at a wave length below the lowest wave length to which the receiver may be tuned.

45 In the accompanying drawing:

Fig. 1 is a circuit diagram illustrative of the invention;

Fig. 2 is a diagram of the equivalent electrical circuit; and

50 Fig. 3 is a representation of curves showing the relation between voltage step-up and wave length.

In the drawing, the numeral 1 identifies the radio frequency amplifier tube which is fed from the input system, the remaining tubes and tube 55 circuits of the receiver being omitted from the

drawing since the particular receiver construction is not an essential feature of the invention. The impedance L_1C_1 across which the tube 1 is connected may be serially connected in the input system, as shown in Fig. 1, or may be coupled in the conventional manner to a coil in the input system.

In addition to the coupling impedance L_1C_1 , the circuit between antenna A and ground G includes the inductance L_e which is serially connected between the antenna and the coupling impedance. The inductance L_e is so chosen that, with its distributed capacity or with added capacity C_e , it resonates at a wave length below the operating range of the receiver.

For a broadcast receiver the impedance L_eC_e may be a radio frequency choke of approximately 1200 microhenries, the geometry of the choke being such that it is resonant at about 180 meters.

The electrical equivalent of the input system is illustrated in Fig. 2, in which the antenna voltage E_0 is impressed across the series circuit which includes the impedance Z_0 of the collecting device, the impedance Z'_0 of the added impedance 80 or choke, and the impedance Z'_1 of the coupling circuit. Each of the three impedances is composite, the impedance Z_0 , for example, comprising resistance R_0 , inductance L_0 and capacity C_0 . The numerical values of these three composite 85 impedances are given by the equations:

$$Z_0 = R_0 \pm jX_0$$

$$Z'_0 = R'_0 \pm jX'_0$$

$$Z'_1 = R'_1 \pm jX'_1$$

In the second and third equations, the terms R'_0 and R'_1 are the effective series resistances; the terms X'_0 and X'_1 are the effective series reactances, and the terms Z'_0 and Z'_1 are the effective series impedances of the respective parallel circuits.

A mathematical analysis will show that, for a given source voltage E_0 , the receiver input voltage E , will be a maximum when the input system is resonant, i. e.,

$$X_0 + X'_0 + X'_1 = 0$$

approximately, and that the receiver input voltage E will be a minimum at the resonant frequency of the added impedance Z_0 .

It is to be noted that this cutoff frequency of input voltage E is dependent only upon the constants of the choke Z_0 , and is independent of the antenna constants. This feature is particularly important in connection with broadcast receivers since greater freedom of set design will 105 110

be possible when the operating characteristics of the receiver are not dependent upon the particular antenna with which it is associated.

The two requirements for the design of the 5 choke impedance Z_c are:

- (1) $X'_c=0$, at a wave length just below the lower operating limit of the receiver, and
- (2) $X'_c+X_o>0$, for wave lengths at the upper limit of the receiver.

10 For broadcast reception, the first requirement may be satisfied by designing the choke for resonance at about 180 meters. To satisfy the second requirement, either the inductance L_c of the choke or the antenna capacity C_o is made relatively large, or both may be given comparatively 15 large values.

The operation of the invention is graphically 20 represented by the curve A of Fig. 3, which shows the variation of voltage step-up with wave length. The input system under measurement was a short outdoor antenna working into an inductance L_c of about 1200 microhenries and a tuned coupling impedance L_1 of 200 microhenries. The data from which curve B was plotted was 25 obtained when the choke inductance L_c was removed to leave the conventional antenna input system.

It is to be noted that the conventional input 30 system gave a voltage step-up at longer wave length which was about one-tenth the step-up at short wave lengths, while the input system constructed in accordance with the invention gave a step-up at 550 meters which was over six times the step-up at 200 meters.

35 It will be understood that the invention is not limited to the particular example which is given above, and that the choke impedance may be appropriately designed for use with receivers operating over other frequency bands, or for effecting a suppression of some particular frequency or band of frequencies within the operating range of the receiver.

I claim:

40 1. An input system for a tuned radio frequency amplifier comprising, in series, a collecting device, an inductive element having sufficient distributed capacity to maintain said element fixedly resonant to a frequency above the frequency range of the amplifier, and an impedance across which said 45 amplifier may be coupled, said inductive element having such constants that the ratio of signal voltage delivered to the amplifier at the low end of said range to that delivered at the high end of the range is increased from a value of the order 50 of 0.1 to a value of the order of 6.

2. In an input system for a tuned radio frequency amplifier, the combination with a collecting device and an impedance across which the input circuit of said amplifier may be coupled, of means for decreasing the voltage step-up at 55 higher frequencies, said means comprising an inductance having a magnitude of the order of 1200 microhenries in series with said collecting device and impedance, and said inductance having distributed capacity and being so designed as to have 60 said capacity in shunt with said inductance and cooperating therewith to exhibit parallel resonance at a frequency adjacent to but higher than the highest frequency to be transmitted to said 65 amplifier.

3. In combination, a source of signal energy, a stage of radio frequency amplification including an electron discharge tube provided with an input circuit, a coupling impedance connected between said input circuit and said source of signal energy, means for tuning said coupling impedance to a desired frequency in a predetermined frequency range, and an inductance element connected in series between said source and said coupling impedance, said inductance element being 70 constructed to be fixedly resonant to a frequency above, but adjacent to, the highest frequency of said range to which said coupling impedance is tunable, and said inductance element having such constants that the ratio of signal voltage impressed on said input circuit to that impressed on said coupling impedance by said source is much greater at the low frequency end of said 75 range than at the high frequency end.

4. In combination, a circuit constituting a 80 source of signal energy, a stage of radio frequency amplification including an electron discharge tube provided with an input circuit, a coupling impedance coupling said input circuit with said 85 first mentioned circuit, means for tuning said 90 coupling impedance to a desired frequency in a predetermined frequency range, and an inductance element connected in said first mentioned circuit in series with said coupling impedance, said inductance element being constructed to be 95 fixedly resonant to a frequency higher than, but adjacent to, the highest frequency of said range to which said coupling impedance is tunable, and said inductance element having such constants 100 that the signal voltage impressed on said input circuit is greater at the low frequency end of said 105 range than at the high frequency end.

PAUL O. FARNHAM.
